SEALING MACHINE

Frank L. Darling, Paterson, N. J., assignor to
Anchor Cap & Closure Corporation, Long Is-
land City, N. Y., a corporation of New York

Application June 20, 1936, Serial No. 86,383

24 Claims. (Cl. 226—84)

The present invention relates to the sealing art and more particularly to a machine for sealing closure caps to containers.

In sealing closure caps to containers it is desirable that the sealing machines be operated rapidly and seal a large number of containers a minute. The objection to most machines is that they are operated intermittently, that is, containers are presented singly to a capping device, 10 are stopped, sealed and thereafter moved away from the sealing station. Machines have been devised to operate continuously with closure caps which are sealed by pressing the caps on the containers. Such machines have used a continuously moving conveyor for presenting the containers to a rotating roller or drum adapted to press the caps into sealed position. These machines are not adapted to seal caps which must be reformed or crimped on the containers and 20 are not suitable for applying caps which require substantial sealing pressure.

Rotary machines have been utilized for more rapid sealing of closures which have to be reformed during their application to containers. 25 Such machines are large, cumbersome, expensive and not satisfactory, since they take up considerable space and are not adapted to work well with filling machines and conveyors.

The present invention aims to overcome or 30 minimize the above difficulties by simplifying the sealing machinery for applying caps to containers and by increasing the speed of operation thereof. The present invention accomplishes this, in part, by sealing a container while it moves 35 continuously on a conveyor, and, in part, by sealing groups of containers simultaneously while they move continuously on a conveyor. The present invention is particularly applicable to closures which require substantial sealing pressure or which must be reformed during the sealing 40 operation to provide a secure seal.

An object of the present invention is to provide a simple, inexpensive sealing machine adapted to seal containers more efficiently.

45 Another object of the invention is to increase the speed of sealing caps to containers.

Another object of the invention is to provide a sealing machine adapted to seal a group of containers simultaneously.

50 Another object of the invention is to provide a sealing machine adapted to seal containers without stopping the movement of the containers as they are delivered to the sealing station.

Another object of the invention is to provide 55 a continuously operated sealing machine adapted

to reform the skirts of the caps as they are sealed upon containers.

Another object of the invention is to provide a sealing machine which may readily be adjusted to accommodate caps and containers of different 5 sizes.

Another object of the invention is to provide a sealing machine wherein the sealing heads or chucks are pneumatically operated.

Another object of the invention is to provide a 10 sealing machine having a pneumatically operated mechanism controlled by automatic devices for rendering the mechanism effective at predetermined intervals.

A further object of the invention is to provide 15 a device for feeding and spacing a group of containers with respect to the sealing mechanism.

Other and further objects of the invention will be obvious upon an understanding of the illustrative embodiment about to be described, or will 20 be indicated in the appended claims, and various advantages not referred to herein will occur to one skilled in the art upon employment of the invention in practice.

A preferred embodiment of the invention has 25 been chosen for purposes of illustration and description and is shown in the accompanying drawings, forming a part of the specification, wherein

Fig. 1 is a side elevational view, partly in section, illustrating a preferred embodiment of the invention;

Fig. 2 is a top plan view illustrating a device for feeding containers to the sealing machine;

Fig. 3 is a sectional view taken along the line 35 3—3 on Fig. 1 of the sealing mechanism;

Fig. 4 is a side elevational view taken along the line 4—4 on Fig. 3;

Fig. 5 is a sectional view of a sealing chuck and a valve for operating the sealing chuck at pre- 40 determined intervals;

Fig. 6 is a diagrammatic top plan view of the sealing chuck valve, illustrating the valve in neutral position A at the start of a cycle, in position to move a chuck down at B, in position to move the chuck up at C, and in neutral position D at the end of a cycle;

Fig. 7 is a side elevational view taken along the line 7—7 on Fig. 6;

Fig. 8 is an end elevational view of the sealing machine;

Fig. 9 is a fragmentary side elevational view of a cam for reciprocating the sealing mechanism carriage taken along line 9—9 on Fig. 8; and 55

Fig. 10 is a diagrammatic view illustrating the operation of the sealing mechanism.

Described generally, the present machine comprises a base or frame upon which the various parts are mounted having a table or runway for a conveyor adapted to continuously move containers from one end of the table to the other. A sealing mechanism with one or more chucks is mounted on a reciprocating carriage above the conveyor and is adapted to move in the same direction and at the same rate of speed as the containers on the conveyor. Suitable automatic devices for rendering the sealing mechanism effective at desired intervals are associated with the carriage. An infeed spider or the like may be utilized for properly spacing the containers on the conveyor with respect to the sealing chucks. A suitable drive mechanism is provided for operating the conveyor, the carriage for the sealing mechanism, and the infeed mechanism.

Referring again to the drawings and more particularly to Figs. 1, 3 and 8 there is shown a machine having a substantially rectangular base or frame 1 with upright members 3 adapted to serve as legs which may be bolted to the floor or other suitable foundation and bracing members 4 at each side of the frame secured to the upright members. Other suitable bracing members may be connected to the upright members 30 to provide a rigid frame construction. A pair of bars or plates 5 are attached to the frame and are spaced apart to provide a longitudinally extending table or runway for a conveyor 6 adapted to move containers from one end of the table to the other. Preferably, the bars extend outwardly beyond both ends of the frame to provide a station at one end for placing the containers on the conveyor and a station at the other end for removing the containers from the conveyor. A suitable angle iron or flanged member 7 is attached to each side of the frame to provide a support for the conveyor (Fig. 3).

The conveyor may comprise a pair of endless chains 9 mounted on suitable sprockets 10 connected to rotatable shafts 11 and 12 supported by the plates 5 at the respective ends of the runway. The chains 9 are spaced apart and extend over the flange members 7 at the respective sides of the runway to provide a channel for the containers. The chains are connected to each other by transversely extending bars 13 adapted to engage the containers to move them along the runway. Preferably, the bars are spaced longitudinally with respect to each other and are adapted to place a container under each sealing chuck simultaneously. In order to operate the conveyor, the sprocket shaft 11 is provided with a gear 14 (Fig. 8) driven by a gear 15 which, in turn, is driven by a gear 16 mounted on a shaft 17 driven by a suitable source of power. A crank 19 may be attached to the shaft 11 for rotating the shaft to operate the machine manually. A belt 20 may be provided beneath the chains 9 for supporting the containers while being moved along the runway which may extend along the edges of the horizontal flanges of the angle irons 7 to prevent sidewise movement. The belt is mounted on a pair of idling rollers 21 rotatably supported by shafts 22 extending through the side plates 5. The belt normally is stationary, but is adapted to be moved with the conveyor while the caps are sealed to the container, as will be described hereinafter. Suitable guide bars 24 may be attached to the frame 75 at each side of the runway for guiding and cen-

tering the containers with respect to the sealing mechanism. The bars, preferably, are adjustable so that they can be moved inwardly and outwardly with respect to the center of the runway to accommodate containers varying in diameter. 5

Referring more particularly to Figs. 1 and 2 a device is illustrated for feeding containers to the conveyor runway in timed relation with respect to the conveyor bars 13, it being understood that other device may also be used for this purpose. 10 The infeed device, preferably, has a platform 25 connected to the frame of the machine and is provided with suitable guide members 26 for guiding the containers to the runway. The guide members 26 are provided with lugs 27 having slots 28 therein for receiving suitable bolts 29 having nuts 30 threaded thereto for attaching the guide members 26 to the platform. The slots 28 preferably are relatively long to facilitate adjusting the position of the guide members 20 to accommodate containers of any suitable diameter. At or near the ends of the guide members 26, adjacent to the conveyor, a latch member or finger 31 is pivotally mounted on the platform which is provided with a projecting portion 32 adapted to extend into the path of the containers and retain the foremost container until one of the bar members 13 has moved past the infeed platform. The finger 31 is normally held in the path of the container by a spring 34 30 but is adapted to be moved out of retaining position by a plurality of projections 35 on a rotatable disc 36 which engage the other end 33 of the finger 31 to oscillate the finger in opposition to the spring 34. In order to move the foremost 35 container at the infeed station to the conveyor runway, a plurality of circumferentially spaced, radially extending transfer arms 37 for engaging the containers are yieldably mounted on a rotatable disc 39. The discs 36 and 39 are mounted on a rotatable shaft 40 and are circumferentially adjustable with respect to each other, so that the projections 35 release the retaining 40 latch prior to the time the transfer arms 37 engage a container. The shaft 40 is rotated by the 45 rotating conveyor shaft 12 through the intermedium of a gear 41 meshing with a gear 42 driven by a sprocket gear 44 connected by a chain 45 to a sprocket gear 46 on the rotating conveyor shaft 12. 50

As the containers are delivered by the conveyor, they pass beneath the frame 1 which supports a longitudinally reciprocating frame or carriage 50 for mounting the sealing mechanism. The carriage 50 comprises a substantially rectangular member 51 for supporting the sealing mechanism provided with rollers 52 adapted to ride on a track such as bars or rods 54 connected to the upright frame members 3 at each side of the machine (Figs. 1 and 3). Downwardly extending uprights 55 are secured to the supporting member 51 and carry an anvil device 56 preferably constructed of suitable plates and bracing members (Figs. 3 and 4) adapted to extend beneath the container supporting belt 20 and serve as a supporting anvil while the caps are being applied to the containers. The anvil 56 preferably is provided with rollers 57 riding beneath suitable rods or bars 59 connected to the frame of the machine. By mounting the upper rollers 52 above the rods 54 and the lower rollers 57 below the rods 59, the carriage 50 cannot move up or down while being reciprocated with respect to the frame. Preferably, the rollers have a recess in their outer periphery such as an 70 75

arcuate groove 60 and the rods are circular as shown herein or have a projection corresponding to the groove in the roller for preventing sidewise movement of the carriage.

5 Any suitable mechanism may be utilized for reciprocating the carriage, but preferably a roller 65 is mounted at one side of the anvil and extends through a slot 66 in an oscillating arm 67 pivotally mounted on the frame at 69. The slot 66 is 10 elongated to compensate for lost motion so that angular oscillating motion of the arm 67 imparts linear motion to the carriage 50. The arm 67 may be oscillated by a connecting rod 70 attached thereto at 71 which is reciprocated by a suitable 15 device such as a cam mechanism (Figs. 1 and 9 which will now be described).

The reciprocating device preferably comprises an eccentric cam 72 mounted on the rotating shaft 17 and a pair of rollers 74 mounted on the 20 connecting rod 70 for engaging the cam at opposite sides thereof. The cam has a contour adapted to move the carriage 50 through a portion of its travel in the same direction and at the same rate of speed as the conveyor, while the sealing 25 mechanism is sealing the caps to the containers and to move the connecting rod in the opposite direction to return the carriage to its initial position after the sealing operation. The connecting rod is slidably mounted on the shaft 17 by means 30 of a suitable longitudinal slot 75 formed in the connecting rod.

The sealing mechanism (Figs. 1, 3 and 4) preferably comprises one or more capping heads 80, here illustrated as three, which are supported by 35 a suitable member 81 attached to the uprights 55 of the carriage by bolts 82 extending through slots 84 in the uprights. Suitable nuts 83 are threaded to the bolts and are adapted to be loosened to slide the supporting member 81 upwardly or downwardly with respect to the uprights to adjust the height of the sealing heads. The nuts may be tightened thereafter to hold the sealing head supporting member in its adjusted position. In order 40 to facilitate raising and lowering the sealing head supporting member 81, suitable threaded rods 85 are connected thereto at 86 and extend upwardly through threaded collars 87 rotatably mounted on the top member 51 of the carriage. The collars are adapted to be rotated by a shaft 89 extending 45 longitudinally along the carriage having worm gears 90 thereon for rotating suitable pinion gears 91 attached to the collars 87. The shaft 89 may be rotated by a handwheel or crank in either direction to raise or lower the heads into a desired 50 position. The threaded rods 85 serve as supporting members while the nuts are loosened, whereby the sealing head is held in adjusted position until the nuts are tightened. The threaded rods 85 are operated simultaneously and maintain the sealing 55 heads in level position while being raised or lowered.

The sealing heads 80 are secured to the supporting member in any suitable manner and are spaced apart approximately the same distance as 60 adjacent container engaging bars 13 on the conveyor chains. In this manner, a container is presented simultaneously to each of the sealing heads and is properly centered with respect to the sealing heads.

70 Referring more particularly to Fig. 5 one of the sealing heads is illustrated in detail. Since all of the sealing heads are alike, a description of the others will be unnecessary. Each head preferably comprises a pneumatic cylinder 95 having a 75 piston 96 therein provided with suitable piston

rings or packing 97. Each piston preferably has an integral downwardly depending sleeve 100 which extends through the bottom of the cylinder and is threaded at its lower end for attaching a suitable cap crimping chuck 101. The chucks may comprise a cylindrical skirt 102 having a flared or tapered annular portion 104 at the inner lower edge thereof for crimping or constricting the skirt of a cap radially inwardly to seal the cap on a container. A suitable anvil 105 for pressing 10 the caps downwardly on the containers while the crimping chuck is effective is mounted on a rod 106 slidably retained in the sleeve 100 by an enlarged portion 107 at the upper end adapted to seat on a shoulder 109 at the upper end of the 15 piston sleeve. If the chuck should accidentally lift a cap from the container, the cap will be ejected from the sealing head, because upon upward movement of the piston the rod 106 engages the top wall of the cylinder and is held stationary 20 while the skirt portion of the chuck moves upwardly with respect to the piston sleeve to eject the cap from the chuck (Fig. 5). While the present machine is particularly adapted to seal crimped caps, it will, of course, be understood that 25 other types of caps may be sealed by substituting suitable sealing heads in the place of those shown herein. For example, the present machine is also adapted to seal caps on containers which require only downward pressure to seal them to the containers, or which reform the skirt or other portions of the cap as desired to form the seal. 30

In order to raise and lower the piston and the capping chucks connected thereto, each cylinder is provided with an inlet 110 for admitting compressed air to the top of the cylinder to move the piston downwardly and an inlet 111 at the bottom of the cylinder for admitting air to move the piston upwardly. Preferably, the inlets 110 of the respective cylinders are connected to a compressed 40 air conduit 112 which is connected to a valve 115. By utilizing a single valve and connecting all the cylinders thereto, the sealing chucks are adapted to be operated simultaneously.

The valve 115 (Figs. 5 and 6) preferably comprises a circular base 117 mounted on the sealing head supporting member 51 having apertures 119 and 120 extending therethrough which are in communication with the conduits 112 and 116 respectively, and a threaded aperture 121 which is 50 in communication with the atmosphere for exhausting pressure on either side of the pistons. A cylindrical casing 122 is threaded to the base 117 and a cover member 123 having a bushing 124 provided with a packing 125 is threaded to the 55 upper end of the casing. If desired, a cap 127 may be threaded to the bushing to retain the packing in position. Compressed air is supplied to the valve by a conduit 126 connected to the cover member 123. 60

In order to control the flow of air to the apertures 119 and 120 and to place the apertures in communication with the exhaust aperture 121, a circular disc 130 is rotatably seated on the upper face of the base member 117 within the casing 65 122. The disc 130 has an aperture 131 (Fig. 6) at the top thereof through which pressure is adapted to pass from the conduit 126 during the operation of the machine and has a circular slot or groove 132 at the underside thereof in communication with the aperture 131 adapted to register with the apertures 119 and 120 alternately (Fig. 6, B and C). Preferably, the slot 132 is formed in the disc so that it may be placed 70 between the apertures 119 and 120 (Fig. 6, A and 75

D). When in this position neither of the apertures 119 and 120 is in communication with air pressure and pressure is shut off to hold the pistons 96 stationary. In order to open the lower 5 end of the cylinder 95 to atmosphere while pressure is effective at the upper side, and vice versa, a circular slot or groove 135 is provided at the underside of the disc 130 adapted to connect the aperture 120 with exhaust aperture 121 (Fig. 6, 10 B) and to connect aperture 119 with the exhaust aperture 121 (Fig. 6, C) alternately at desired intervals. The disc 130 is adapted to be rotated by a shaft 139 extending through the bushing 124 and having a key 137 at the lower end adapted 15 to fit into a key slot 136 formed in the disc. The shaft has an arbor portion at its upper end for mounting an operating arm 140 which is held in place by a nut 141 threaded to the upper end of the shaft.

20 The arm 140 is adapted to be turned to operate the valve by contact projections such as dogs 142 and 144 (Fig. 6) attached to the top frame members 4. Preferably the dog 142 is on the front side of the machine (Figs. 1 and 6) substantially at the end where the containers are fed by the conveyor, while the dog 144 is mounted on the back of the machine further away from the feed end of the frame. When the sealing head carriage is moved in the same direction as the 30 conveyor, the dog 142 engages one end of the arm and turns it to operate the valve to admit air to the top of the sealing head cylinders, which causes downward movement of the sealing chucks. Upon further movement of the carriage the dog 35 144 engages the other end of the arm and turns it to operate the valve to admit air to the bottom of the sealing head cylinders which cause the sealing chucks to be raised upwardly. A third dog 145 is bolted to one of the frame members 4 at the end of the frame where the containers 40 leave the machine, which turns the arm to place the valve in neutral position (Fig. 6, A and D) so that compressed air is shut off and the sealing head pistons are held stationary.

45 In Fig. 7 one of the valve arm operating dogs is shown in detail, together with the arm 140, the latter being shown in section. Since both dogs 142 and 144 are substantially similar, only one need be described in detail. The dogs preferably comprise a pivotally mounted latch member or finger 146 having a projection 147 at its free end adapted to engage the side portion 149 of the arm 140. The finger is pivoted at 150 on a bracket member 151 and is held in position by 50 a flat spring member 152 bolted to the bracket. In order that the arm be turned to operate the valve only when the sealing head carriage is moved in the direction with the containers and not be turned when moved in the opposite direction, the finger is provided with a cam face 154 adapted to be engaged by a cam surface 155 on the arm 140 to move the finger or latch member downwardly in opposition to the spring 152. In this manner, the arm 140 is forced over the 55 latch members and is not rotated to operate the valve while the sealing head carriage is moved back into its initial position. The brackets 151 for mounting the dogs 142 and 144 may be attached to the frame members 4 by bolts 153 at 60 any suitable position with respect to the end of the frame to operate the valve at desired intervals. In this manner the position of the dogs with respect to each other and the end of the frame may be adjusted to vary the sealing chuck 65 operating cycle.

The valve 115 and the sealing chuck cylinder 95 preferably are lubricated by attaching an oil cup 156 to the compressed air conduit 126 (Fig. 1). Oil is permitted to drip slowly into the conduit 126 and is forced into the valve and cylinders by the compressed air. Excess oil is prevented from being sprayed through the exhaust port 121 and on the containers by a conduit 157 (Fig. 3) attached to the exhaust port 121 and extending to the bottom of the machine (Fig. 1). The outlet 10 end of the conduit 157 may be provided with a perforated baffle member 159 adapted to prevent spraying of oil when pressure is released from the cylinders.

The machine illustrated and described herein 15 may be driven by any suitable source of power, but preferably a motor 160 (Fig. 1) is mounted at the bottom of the frame. The motor may be connected to a speed reduction gear 161 or the like 20 adapted to rotate a sprocket gear 162 on the shaft 17 by means of a chain 164. The gear 162 rotates the shaft 17 to operate the cam 12 and to 25 rotate the conveyor operating gears which, in turn, operate the container feeding device. The drive means may be concealed within the frame 25 by suitable plates 165 removably attached to the lower end of the upright frame member 3 and the runway member 5.

To operate the machine the container feeding 30 guides are adjusted to accommodate the containers to be sealed and the longitudinally extending container guides 23 are adjusted to center the containers with respect to the sealing heads. The height of the sealing head support is adjusted, so that the chucks are in proper position to apply the caps to the containers, by rotating the rod 89 to rotate the screw members 85. Thereafter, the conveyor chain is adjusted to position the bars 13 with respect to the sealing chucks so that containers will be directly beneath the chucks when the sealing head carriage is at the sealing station. This may be done by disconnecting the 35 chain sprockets 10 from the shaft and rotating the sprockets manually until the containers are under the sealing heads while the sealing chucks are effective. The infeed spider is then adjusted to feed a container from the infeed platform just before one of the conveyor bars moves upwardly behind the container. Thereafter the sprockets are secured to the shaft to facilitate rotation 40 thereof when the machine is operated. After these preliminary adjustments have been made the machine may be operated manually by turning the handle 19 to see that all the parts move freely and that the sealing chucks and containers move in proper relation with respect to each other. The compressed air may then be turned on, while the machine is operated manually to 45 determine whether or not the cylinders and chucks operate properly. If necessary, the contact dogs 142 and 144 may be adjusted on the frame members 4 to operate the valve at correct intervals. The machine may now be started by 50 starting the motor which causes the infeed spider to feed containers to the conveyor, the conveyor to move containers continuously under the sealing frame, and the sealing frame or carriage to move with the containers while the sealing chucks are operated by air pressure.

The operation of the sealing chucks during the 55 sealing cycle is illustrated more particularly in Figs. 4, 5, 6 and 10. First, the carriage is moved to the right hand end of the frame (Fig. 10) while the valve is in neutral position (Fig. 6A) and a group of containers having caps loosely 60

seated thereon move under the chucks. The carriage now is moved by the cam 72 and connecting means in the same direction and at the same rate of speed as the conveyor, while the valve arm 140 engages the dog 142 (Fig. 6B) to operate the valve to admit air to the upper ends of the cylinders whereby the chucks move downwardly simultaneously and seal the caps to the containers (Fig. 5 in dotted lines and Fig. 10). As the carriage continues to move with the containers, the other end of the valve arm 140 engages the dog 144 (Fig. 6C) to operate the valve to open the upper end of the cylinders to atmosphere by means of the exhaust port and to admit air to the lower ends of the cylinders whereby the chucks move upwardly simultaneously out of engagement with the caps (Fig. 10 in dotted lines). The conveyor then continues to move the sealed containers to the delivery end of the machine where they are removed while the sealing head carriage stops as it reaches the end of the frame. At this point the valve arm engages the contact projection 145 and turns the valve into neutral position (Fig. 6D). The cam 72 thereafter is effective to move the carriage towards the other end of the frame until it is back in starting position for the succeeding cycle of operation. During the return of the sealing head carriage, a succeeding group of containers is delivered by the conveyor. While the carriage is being moved back into starting position, the valve arm 140 remains in neutral position and is forced over the resiliently mounted latches of the dogs. The supporting anvil 56 beneath the belt moves with the sealing chucks to provide a rigid support for the containers during the sealing operation. The containers while being sealed are forced downwardly on the belt which causes the belt to be pressed against the anvil and move with the containers and the anvil. The belt preferably is made of leather or the like and is adapted to act as a cushion for the containers when they are pressed downwardly on the anvil.

While the sealing machine is described as being air operated, it will be understood that the sealing chucks may be operated by any suitable mechanical or electrical devices. Also, if desired, the sealing chucks may be moved downwardly by air pressure and moved upwardly by spring means or vice versa. Various other changes may be made within the scope of the invention.

It will be seen that the present invention provides a simple efficient machine for sealing containers moving continuously beneath the machine in a straight line. The sealing chucks are effective while moved with the containers, whereby the containers need not be stopped individually at the sealing station. Also complicated devices for operating the machine intermittently are eliminated. The continuous movement of the containers increases the speed of the machine and enables the machine to be connected directly with a suitable filling machine. By sealing a group of containers simultaneously, the sealing capacity of the machine is further increased without operating the machine at an excessive rate of speed. The machine may be readily adjusted for containers of various sizes and shapes and the sealing chucks may be interchanged to accommodate various sizes of caps. The machine is rugged in construction and can readily withstand any rough usage to which it may be subjected.

As various changes may be made in the form, construction and arrangement of the parts herein without departing from the spirit and scope

of the invention and without sacrificing any of its advantages, it is to be understood that all matter herein is to be interpreted as illustrative and not in a limiting sense.

Having thus described my invention, I claim:

1. In a sealing machine, the combination of a conveyor for moving a group of containers beneath a sealing mechanism, a sealing mechanism having a plurality of sealing chucks for simultaneously sealing the group of containers, means for moving the sealing mechanism at the same rate of speed and in the same direction as the group of containers, a normally stationary endless belt beneath said conveyor for supporting the containers and means for rotatably mounting said belt to permit movement of said belt with said containers while said sealing mechanism is sealing the containers and is moving with the containers.

2. In a sealing machine, the combination of means for moving a container in a straight line under a sealing mechanism, a reciprocable sealing mechanism having a pneumatically operated sealing chuck for sealing a cap to the container, means for moving said sealing mechanism in the same direction and at the same speed as the container to move said chuck in vertical alignment with the container, and means responsive to the movement of said sealing mechanism adapted to cause said chuck to be operated.

3. In a sealing machine, the combination of means for moving a group of containers in a lineal direction, a sealing mechanism having a group of pneumatically operated sealing chucks for simultaneously sealing caps to the containers, means for moving the sealing mechanism at the same rate of speed and in the same direction as the group of containers to bring said chucks in vertical alignment with the containers and for returning the sealing mechanism to its initial position, and valve means operated during the movement of said sealing mechanism for periodically rendering the chucks effective to seal caps to the containers.

4. In a device of the class described, the combination of a conveyor adapted to deliver containers to a sealing mechanism, a support for a sealing mechanism periodically movable with said conveyor, a pneumatic cylinder mounted on said support, a piston in said cylinder, a capping chuck operatively connected to said piston, a valve adapted to admit air to the upper end of said cylinder to move said piston and chuck downwardly and adapted to admit air to the lower end of said cylinder to move said chuck and piston upwardly, and means for operating said valve at predetermined intervals.

5. In a device of the class described, the combination of a conveyor adapted to deliver a group of containers to a sealing mechanism, a slidable support for a sealing mechanism, means for periodically moving said support with said conveyor, a group of air cylinders, a piston in each of said cylinders having a capping chuck connected thereto, a valve adapted to simultaneously admit air to the upper end of each of said cylinders to move said pistons and chucks downwardly and adapted to simultaneously admit air to the lower end of each of said cylinder to move said chuck and piston upwardly, and means for operating said valve at predetermined intervals.

6. In a device of the class described, the combination of a conveyor for delivering containers to a sealing mechanism, an air operated cylinder above said conveyor having a piston therein and

- a sealing chuck operatively connected to said piston for applying caps to the container, means for periodically moving said cylinder in the same direction and at the same rate of speed as the containers are moved by the conveyor and for returning said cylinder to its initial position, a valve movable with said cylinder for admitting air to the upper end of said cylinder to move said piston and chuck downwardly to seal a cap and for admitting air to the lower end of said cylinder to move said piston and chuck upwardly, an arm carried by said valve for operating said valve, a stationary member adapted to move said arm and cause said valve to admit air to the upper end of said cylinder when said valve arm is moved into contact therewith.
7. In a device of the class described, the combination of a conveyor for delivering containers to a sealing mechanism, an air operated cylinder above said conveyor having a piston therein, a sealing chuck operatively connected to said piston for applying caps to the container, means for periodically moving said cylinder in the same direction and at the same rate of speed as the containers are moved by the conveyor and for returning said cylinder to its initial position, a valve movable with said cylinder for admitting air to the upper end of said cylinder to move said piston and chuck downwardly to seal a cap and for admitting air to the lower end of said cylinder when said valve arm is moved into contact therewith.
8. In a device of the class described, the combination of a conveyor for delivering containers to a sealing mechanism, an air operated cylinder above said conveyor having a piston therein and a sealing chuck operatively connected to said piston for applying caps to the container, means for periodically moving said cylinder in the same direction and at substantially the same rate of speed as the containers are moved by the conveyor and for returning said cylinder to its initial position, a valve movable with said cylinder for admitting air to the upper end of said cylinder to move said piston and chuck downwardly to seal a cap and for admitting air to the lower end of said cylinder to move said piston and chuck upwardly, said valve having a conduit therein for opening the lower end of said cylinder to atmosphere while air is admitted to the upper end and for opening the upper end when air is admitted to the lower end, an arm for operating said valve carried by said valve, a stationary member adapted to engage and move said arm and cause said valve to admit air to the upper end of said cylinder when said cylinder is moved into a predetermined position, and a second stationary member adapted to move said arm and cause said valve to admit air to the lower end of said cylinder when said cylinder is moved into a second predetermined position.
9. In a device of the class described, the combination of a conveyor for delivering containers to a sealing mechanism, an air operated cylinder above said conveyor having a piston therein and a sealing chuck operatively connected to said piston for applying caps to the container, means for periodically moving said cylinder in the same direction and at substantially the same rate of speed as the containers are moved by the conveyor and for returning said cylinder to its initial position, a valve movable with said cylinder for admitting air to the upper end of said cylinder to move said piston and chuck downwardly to seal a cap and for admitting air to the lower end of said cylinder to move said piston and chuck upwardly, said valve having a conduit therein for opening the lower end of said cylinder to atmosphere while air is admitted to the upper end and for opening the upper end when air is admitted to the lower end, an arm carried by said valve for operating said valve, a stationary member adapted to engage and move said arm and cause said valve to admit air to the upper end of said cylinder when said cylinder is moved into a predetermined position, and a second stationary member adapted to move said arm and cause said valve to admit air to the lower end of said cylinder when said cylinder is moved into a second predetermined position.

engage and move said arm and cause said valve to admit air to the lower end of said cylinder when said cylinder is moved into a second predetermined position, and a third stationary member adapted to engage said arm after the chuck has been moved upwardly and to move said arm to cause the valve to prevent air from being admitted to both the upper and lower end of said cylinder.

10. In a device of the class described, the combination of a conveyor for delivering a group of containers to a sealing mechanism, a group of air cylinders above said conveyor each having a piston therein adapted to move upwardly and downwardly and a capping chuck operatively connected to each piston, means for moving said cylinders in the same direction and at the same rate of speed as said containers to periodically cause each cylinder to move in vertical alignment with one of the containers, a valve for causing the pistons and chucks to move at desired intervals, means for operating said valve to admit air to said cylinders to move said chucks downwardly, and means for operating said valve to admit air to said cylinder to move said chucks upwardly.

11. In a device of the class described, the combination of a conveyor for delivering a group of containers to a sealing mechanism, a group of air cylinders above said conveyor each having a piston therein adapted to move upwardly and downwardly and a capping chuck operatively connected to each piston, means for moving said cylinders in the same direction and at the same rate of speed as said containers to periodically cause each cylinder to move in vertical alignment with one of the containers, a valve for causing the pistons and chucks to simultaneously move upwardly and downwardly at desired intervals, means for operating said valve to admit air to said cylinder to move said chucks downwardly, and means for operating said valve to admit air to said cylinder to move said chucks upwardly, said means for operating said valve being adjustable to determine when said chucks are moved upwardly and downwardly.

12. In a sealing machine, a frame, a sealing mechanism slidably mounted on said frame having an air cylinder for actuating a capping chuck in combination with a valve mounted on said sealing mechanism for operating said cylinder comprising a cylindrical casing provided with an upstanding wall and a base having a conduit for admitting air to the upper end of said cylinder, a second conduit for admitting air to the lower end of said cylinder, and a third conduit for opening the valve to atmosphere, a disc member seated on said base member having a groove therein adapted to register with the conduits of said base member, an aperture in communication with said groove for admitting air to said cylinder conduits, a cover member for said valve casing, and means rotatably mounted in said cover member for rotating said disc to operate said valve said frame having stationary means for engaging said last means to effect rotation thereof.

13. In a device of the class described, the combination of a frame for a sealing machine, a pair of parallel rods connected to said frame, a carriage having rollers thereon adapted to ride on said rods to movably mount said carriage on said frame, a second pair of rods, rollers on said carriage extending underneath said second pair of rods adapted to hold said carriage

against upward movement, a sealing mechanism supported by said carriage, and means for reciprocating said carriage.

13. In a device of the class described, the combination of a base for a sealing machine, a pair of parallel rods connected to said base, a carriage having rollers thereon adapted to ride on said rods to movably mount said carriage on said base, a sealing mechanism supported by said carriage, an anvil beneath said sealing mechanism connected to said carriage for supporting containers to be sealed, and means for reciprocating said carriage.

14. In a device of the class described, the combination of a base for a sealing machine, a pair of parallel rods connected to said base, a carriage having rollers thereon adapted to ride on said rods to movably mount said carriage on said base, a sealing mechanism supported by said carriage, a sealing anvil connected to and movable with said carriage and said sealing mechanism, means for reciprocating said carriage on said rods, and a conveyor for delivering containers beneath said sealing mechanism.

15. In a device of the class described, the combination of a base for a sealing machine, a pair of parallel rods connected to said base, a carriage having rollers thereon adapted to ride on said rods to movably mount said carriage on said base, a sealing mechanism supported by said carriage, a sealing anvil connected to and movable with said carriage and said sealing mechanism, means for reciprocating said carriage on said rods, a conveyor above said anvil for delivering containers beneath said sealing mechanism, and means for delivering containers to said conveyor.

16. In a device of the class described, the combination of a belt mounted on a pair of idling rollers, a conveyor comprising a pair of chains having container engaging bars connecting the respective chains, a sealing mechanism above said conveyor, and a container supporting anvil beneath said belt.

17. In a device of the class described, the combination of a belt mounted on a pair of idling rollers, a conveyor for delivering containers on said belt, a sealing mechanism above said conveyor adapted to move with said conveyor at predetermined intervals, a container supporting anvil beneath said belt, and means for moving said sealing mechanism and supporting anvil with said conveyor while said sealing mechanism is effective to seal a cap on a container.

18. In a sealing machine, the combination of a conveyor for moving a container in a straight line, a movable carriage adapted to be reciprocated, a sealing mechanism supported by said carriage for sealing a cap to the container, means for moving said carriage and sealing mechanism in a horizontal plane and in the same direction and at the same speed as the container while said sealing head is effective, and supporting means beneath said conveyor connected to said carriage and movable with said sealing mechanism.

19. In a sealing machine, the combination of means for moving containers in lineally spaced relation under a sealing mechanism, a sealing mechanism having a plurality of pneumatically operated sealing chucks for sealing caps to the containers, means for periodically reciprocating said sealing mechanism in a horizontal plane and in the same direction and at the same speed as the containers to move said chucks into ver-

tical alignment with the containers, and means operated by movement of said sealing mechanism to render said sealing mechanism effective to seal the caps to the containers while said chucks are in alignment with the containers.

20. In a device of the class described, the combination of a conveyor adapted to deliver containers to a sealing mechanism, a belt beneath said conveyor for supporting the containers, a support for a sealing mechanism periodically movable with said conveyor, a pneumatic cylinder mounted on said support, a piston in said cylinder, a capping chuck operatively connected to said piston, a valve adapted to admit air to the upper end of said cylinder to move said piston and chuck downwardly and adapted to admit air to the lower end of said cylinder to move said chuck and piston upwardly, and means for operating said valve at predetermined intervals.

21. In a device of the class described, the combination of a conveyor adapted to deliver containers to a sealing mechanism, a support for a sealing mechanism periodically movable with said conveyor, a fluid pressure cylinder mounted on said support, a piston in said cylinder, a capping chuck operatively connected to said piston, a valve adapted to admit fluid pressure to the upper end of said cylinder to move said piston and chuck downwardly and adapted to admit fluid pressure to the lower end of said cylinder to move said chuck and piston upwardly, means for operating said valve at predetermined intervals, and an anvil member connected to said support and movable therewith adapted to support the containers while said capping chuck is moved downwardly.

22. In a device of the class described, the combination of a frame for a sealing machine, a conveyor adapted to deliver containers to a sealing mechanism, a support for a sealing mechanism slidably mounted on said frame and periodically movable with said conveyor, a capping chuck, pneumatic means for moving said chuck downwardly and upwardly, a valve adapted to admit air to said pneumatic means at predetermined intervals, and means on said frame for operating said valve in response to the movement of said support.

23. In a device of the class described, the combination of a frame for a sealing machine, a conveyor adapted to deliver containers to a sealing mechanism, a support for a sealing mechanism slidably mounted on said frame and periodically movable with said conveyor, capping means on said support, pneumatic means for moving said capping means downwardly and upwardly, a valve on said support adapted to admit air to said pneumatic means at predetermined intervals, and means adjustably mounted on said frame for operating said valve in response to the movement of said support to determine the intervals at which said valve is operated.

24. In a sealing machine, the combination of a support, a conveyor for moving a group of containers in a straight line over said support, a sealing mechanism having a plurality of sealing chucks for simultaneously sealing the group of containers, and reciprocating means for moving the sealing mechanism and support parallel with respect to said conveyor, and at the same rate of speed and in the same direction as the group of containers when said sealing chucks are effective.
